CLAIM

The ornamental design for a tone wheel, as shown and described.

DESCRIPTION

FIG. 1 is a front perspective view of a first embodiment of a tone wheel, showing my new design.

FIG. 2 is rear perspective view thereof;

FIG. 3 is a front view thereof;

FIG. 4 is a left side view thereof; the right side being a mirror image thereof;

FIG. 5 is a rear view thereof;

FIG. 6 is a right side sectional view taken in the direction of line 6-6 of FIG. 3;

FIG. 7 is a front perspective, exploded view thereof; and

FIG. 8 is a left side exploded view thereof;

FIG. 9 is a front perspective view of a second embodiment of a tone wheel, showing my new design.

FIG. 10 is rear perspective view thereof;

FIG. 11 is a front view thereof;

FIG. 12 is a left side view thereof; the right side being a mirror image thereof;

FIG. 13 is a rear view thereof;

FIG. 14 is a right side sectional view taken in the direction of line 14-14 of FIG. 11;

FIG. 15 is a front perspective, exploded view thereof; and,

FIG. 16 is a left side exploded view thereof.
